SKI BOOT HEEL CONSTRUCTION

Arthur Guindon, St. Jerome, Quebec, Canada

Application December 26, 1947, Serial No. 793,855

4 Claims. (Cl. 36—2.5)

1

The present invention relates to a ski boot heel.

More specifically, this invention relates to a heel, particularly adaptable for ski boots, which consists of a peripheral heel plate having interior stepped portions for receiving leather inserts, the whole being secured to the footgear by fastening elements which extend through said inserts.

With most footgear, the greater wear and strain takes place at the heel. It is therefore desirable that the heel should be of the strongest and most durable construction, and should be firmly secured to the sole of the boot or shoe.

In the case of ski boots, the strain and wear on the heel is greatly increased in use, for the harness of the skis is usually secured to the boot by frictional engagement with a peripheral groove in the heel. Whilst skiing, the harness continually tends to wear away the edges of this groove (and thus destroy the intimate connection between ski boot and ski) and also to loosen the means securing the heel to the boot.

It is also true that normal wear in ski boots, as when walking, tends to erode the bottom of the heel and hence destroy the harness-engaging lower edge of the groove. In either case, extensive repairs or total replacement of the heel must be carried out after certain use.

The main object of the present invention is to provide an improved ski boot heel, the harness-engaging means of which are adapted to withstand wear either by the harness or in walking.

Another important object is to provide a ski boot heel construction characterized by an improved and strengthened connection between the heel and boot.

Yet another object resides in the provision of a ski boot heel construction wherein, even after unduly long wear, only minor repairs need be carried out to renew the heel.

And still another object resides in the provision of a ski boot heel construction of the character described which is simple in design and of light, waterproof construction.

Other objects and advantages will become apparent, or be further pointed out in the description to follow.

As an example, and for purposes of illustration only, a preferred embodiment of my invention is shown in the annexed drawing, wherein:

Fig. 1 shows a side elevation of a ski boot fitted with a heel according to the invention;

Fig. 2 shows a perspective view of a typical plate comprising the periphery of such a heel;

Fig. 3 shows a longitudinal mid-sectional ele-

2

vation through a heel in position secured to a ski boot;

Fig. 4 shows a detail section through the peripheral heel plate, and

Fig. 5 shows a perspective view of a ski boot, the rear portion of whose sole has been shaped to receive the present heel.

Referring now to the drawing, wherein the same reference characters denote corresponding parts throughout, the heel construction H of this invention has as its main component a peripheral heel plate indicated at 6, the sole of a boot B with which the heel is associated being shaped suitably to receive this plate which is held 10 thereagainst by a number of leather pads or inserts 7, 8 and 9, these latter being riveted, or otherwise secured, to the sole of the boot.

Figs. 2, 3 and 4 best show the heel plate 6. Within limits defined by the size of boot B, this 20 plate may adopt various sizes and shapes but is preferably horseshoe or U-shaped, the rounded portion constituting the rear thereof, and has a transverse bar 10 connecting the ends. The outer surface of the horseshoe plate comprises the periphery of the heel and has, accordingly, a groove 11 adapted to receive a ski harness extending for substantially the full length therearound.

Inside plate 6, the surface thereof is stepped inwardly both from the top and the bottom to receive, respectively, appropriately-shaped layers of the sole of boot B and leather pads or inserts such as 7 and 8. Thus, in the preferred embodiment illustrated, a square-edged ridge or shoulder 12 projects inwardly from the mid portion of the inner surface of the plate for substantially the full distance therearound. Above this shoulder, the U-shaped plate has a vertical inner surface for a short distance and then slopes outwardly as at 13 towards the top. Below the shoulder, the bar 10 extends transverse 40 the forward ends of the horseshoe, and both the bar and plate are provided, on their inner surfaces, with a single outward step 14 in the direction of the bases thereof.

It will be presumed that boot B is provided with a multi-layer sole having at least two exterior layers such as 16 and 17 at the rear portion thereof, although this need not be true in all cases. Figures 3 and 5 show that the bottom sole layer, 17, is of reduced dimensions as compared with 16, and is shaped to fit inside shoulder 12 of plate 6. Sole 16, on the other hand, will rest on top of shoulder 12 whilst the heel portion of the upper of the boot will abut against, and 55 be received in, the sloping inner surface 13 of

the plate. When the latter has been thus positioned against the boot, the flat leather pads or inserts will be packed into place. The smaller insert, 7, is shaped to fit against the lower surface of shoulder 12 whilst insert 7 will be received in the recess formed between step 14 and the bottom edges of plate 6 and bar 10. A heel tread 9, shaped to cover the bottom of the plate, is then placed at the base of the heel and secured, as by means of rivets 18, to the inner sole of the boot. By this means the several layers of inserts and soles are all firmly tightened and the composite heel is securely held in place.

It will be preferable that, to avoid sharp cutting edges on the heel, bar 10 be wedge-shaped or triangular in section from front to rear. That is, from the flat upper surface which abuts the underneath of sole 11, the bar will be inclined from front to rear towards the bottom of plate 6.

Considering Figure 3, it is apparent how the objects and advantages of this type of heel construction are realized. Since plate 6 may be of some metallic or other durable material, obviously even prolonged wear by the harness of skis will not impair the gripping qualities of groove 8 since the edges of the latter will not erode appreciably. And even when the tread 9 of the heel has become worn from walking and the like, the plate will continue to resist impairing of the heel. Moreover the heel may be completely restored by simply replacing the worn tread thereof. As for the increased strength preventing the harness from pulling the heel off the boot, this is attributable to the fact that the sole of the boot is not secured to the top of the heel, but extends well down into, and forms part of, the heel construction. Finally, by making the plate out of some light material, for instance aluminum, the heel may be made as light as those presently in use.

It will be understood that I do not limit myself to the particular embodiment of my invention herein shown and described, but that various changes may be made in the size, shape and arrangement of parts without departing from the spirit of the invention or the scope of the subjoined claims.

Having thus described my invention, I claim:

1. A heel construction affixable to the sole of a boot and especially adapted to ski boots, said construction comprising a hard, U-shaped plate adapted to form the heel periphery, said plate recessed in the upper interior portion to receive said sole, a bar across the ends of said plate adapted to abut the sole, said plate recessed in the lower interior portion, packing elements adapted to be fitted into the lower portion of the plate, a tread shaped to enclose the bottom of said plate and bar, and means for securing said tread to said sole.

2. A heel construction adapted to be affixed to ski boot soles and comprising: a U-shaped plate constituting the heel periphery, a bar across the ends of said plate adapted to abut the sole of a boot in front of the heel, the inside surface of said plate being stepped inwardly from the top and bottom thereof and adapted to receive the ski boot sole in the upper portion thereof, leather-like inserts adapted to be packed inside the lower portion of said plate, a heel tread shaped to enclose the bottom of said plate and means for securing said tread to the sole of the boot in order to clamp the composite heel in place.

3. A heel construction affixable to ski boot soles comprising: a U-shaped plate adapted to form the periphery of a heel and having an exterior ski-harness-receiving groove and an interior shoulder projecting from the mid-portion of the inner surface thereof for substantially the full length therearound, the rounded portion of said plate constituting the rear of the heel, a bar across the ends of said plate below said shoulder and adapted to abut the ski boot sole, the interior surface of said plate stepped inwardly toward the shoulder from the top and bottom and adapted to receive said ski boot sole in the upper portion thereof, leather inserts adapted to be packed inside the lower portion of the plate, a heel tread shaped to enclose the bottom of said plate, and means for securing said tread to said ski boot sole to clamp the heel in place.

4. In a ski boot heel construction as claimed in claim 2, said plate having a ski-harness-receiving groove extending around the periphery thereof.

ARTHUR GUINDON.
